(57) **CLAIM**

The ornamental design for pet furniture, as shown and described.

DESCRIPTION

FIG. 1 is a front, right, top perspective view of pet furniture showing my new design;

FIG. 2 is a front, right, bottom perspective view thereof;

FIG. 3 is a front elevation view thereof;

FIG. 4 is a rear elevation view thereof;

FIG. 5 is a left side elevation view thereof;

FIG. 6 is right side elevation view thereof;

FIG. 7 is a top plan view thereof; and,

FIG. 8 is a bottom plan view thereof.

The broken lines show features of the pet furniture that form no part of the claimed design.

1 Claim, 8 Drawing Sheets
